United States Patent Office

Des. 232,619

Patented Sept. 3, 1974

232,619

ADHESIVE GUN

Gerald W. Crum, Elyria, Ohio, assignor to Nordson
Corporation, Amherst, Ohio

Filed Mar. 23, 1973, Ser. No. 344,093

Term of patent 14 years

Int. Cl. D8—05

U.S. Cl. D8—30

Fig. 4

Fig. 5

Fig. 6

Fig. 10

Fig. 11

Fig. 12

FIG. 16

FIG. 17

FIG. 18

FIG. 1 is a perspective view taken from the right rear side of a first embodiment of an adhesive gun showing my new design;

FIG. 2 is a rear view of that first embodiment shown in FIG. 1;

FIG. 3 is a front view of that first embodiment shown in FIG. 1;

FIG. 4 is a perspective view taken from the left front side of that first embodiment shown in FIG. 1;

FIG. 5 is a top view of that first embodiment shown in FIG. 1;

FIG. 6 is a bottom view of that first embodiment shown in FIG. 1;

FIG. 7 is a perspective view taken from the left rear side of a second embodiment of an adhesive gun showing my new design;

FIG. 8 is a rear view of that second embodiment shown in FIG. 7;

FIG. 9 is a front view of that second embodiment shown in FIG. 7;

FIG. 10 is a perspective view taken from the left front side of that second embodiment shown in FIG. 7;

FIG. 11 is a top view of that second embodiment shown in FIG. 7;

FIG. 12 is a bottom view of that second embodiment shown in FIG. 7;

FIG. 13 is a perspective view taken from the right rear side of a third embodiment of an adhesive gun showing my new design;

FIG. 14 is a rear view of that third embodiment shown in FIG. 13;

FIG. 15 is a front view of that third embodiment shown in FIG. 13;

FIG. 16 is a perspective view taken from the left front side of that third embodiment shown in FIG. 13;

FIG. 17 is a top view of that third embodiment shown in FIG. 13; and

FIG. 18 is a bottom view of that third embodiment shown in FIG. 13.

I claim:

The ornamental design for an adhesive gun, substantially as shown and described.
